THREAD OR THE LIKE WINDING AND
ADVANCING REEL

Thomas S. Mayner, Chagrin Harbor, Willoughby Township, Lake County, Ohio, assignor to Industrial Rayon Corporation, Cleveland, Ohio, a corporation of Delaware

Application April 16, 1947, Serial No. 741,739

7 Claims. (Cl. 28—71.7)

1

This invention relates to a thread or the like winding and advancing reel. More particularly, the invention relates to a reel that is adapted to either store a considerable length of the thread or the like without advancing it, or to advance the store of thread over its periphery in a plurality of generally helical turns.

The reel of this invention will be described with reference to a cantilever type reel although it can be supported from both ends if so desired. Because of the easy accessibility of cantilever reels and their adaptability to an open-faced machine they are advantageously used in a continuous process machine for the manufacture of artificial thread or the like. In such a machine the reels are adapted to be positioned in a manner so as to enable a sequential performance of a series of individual processing steps on the thread.

Generally, thread-advancing reels are made of two cage-like reel members. Each of the reel members has a periphery of a plurality of bar members. The two reel members are combined so that their respective bar members are in an interleaved relation, the combination forming a generally circular periphery. The advancement of the thread or the like is effected by an emergence and a forward thrust of one set of the two sets of bar members outside the common reel periphery, once during each revolution of the reel. The advancement of the thread is usually effected in single increments, i. e., the thread is caused to move forward a predetermined distance but one during each revolution of the reel.

It has been proposed to increase the rate of thread advancement by oppositely rotating the offset axis of the reel member which causes the thread to advance. While this may produce an increase in the advancement of thread, nevertheless, there still remains the fact that the thread is advanced in substantially single increments during each revolution of the reel. Also, while the thread is substantially continuously advanced in single increments, such an advancement is somewhat abrupt.

The travel of thread is advantageously made more uniform and the abruptness of a two-member reel is considerably lessened by the reel of this invention. The reel advances the thread in at least two increments during each 360° period of rotation. The reel comprises at least three reel-members two of which are adapted to advance thread over the reel periphery during each reel revolution. Other things being equal the rate of thread advancement is greater over such a reel inasmuch as the thread is moved in a

forward direction on the reel at least twice during each reel revolution. In addition to the aforesaid the advancement of thread or the like over the reel can be stopped when desired by causing the reel to act substantially as a cylinder whereon the thread is only wound but not advanced.

The reel advantageously comprises at least three cage-like members, mounted on axes which are offset and askew to each other. The principle of operation is substantially similar to that described in the Knebusch Patent No. 2,210,914. The reel member axes are positioned relative to each other so as to cause an emergence of one set of bar members at substantially the moment when another set of bar members is beginning to recede. The projection of each such set of bar members is had in a sequential manner so that the thread is advanced in at least two forward movements, one following the other, during each revolution of the reel.

Advantageously, at least two reel members are mounted on eccentrics, i. e. on offset and askew axes, that are subject to an external control, such as a clutch device, the manipulation of which will permit the eccentrics to either rotate or remain stationary. When the eccentrics are kept from rotation the thread is caused to advance over the reel; however, when the eccentrics are rotated at a speed equal to the driving shaft of the reel the thread will merely wind on the reel. In a two-member reel where one of the reel members rotates about an eccentric, that eccentric is then similarly subject to control. It can be held from rotation or fixed to the rotating reel shaft.

Since the reel is a cantilever type reel it is driven from one end only. The mechanism for changing the reel from a non-advancing to an advancing type is desirably located at the driving end of the reel. Furthermore, the driving gear may be mounted on a one-way clutch to permit relative increased rotation between the driving means and the reel in a forward direction in the event that there may occur a faster withdrawal of thread off the reel than when it is laid or taken-up by the reel, for instance, initially formed thread from a spin bath.

The aforesaid reel and its advantages will be described in greater detail in the following specification and the accompanying drawing where:

Figure 1 is side elevation of the reel;

Figure 2 is a front elevation of the reel of Figure 1;

Figure 3 is a cross section of the reel of Figure 1;

Figure 4 represents the eccentric reel-member mountings;

Figure 5 represents, in cross section, the mechanism for causing the reel to become, generally, a cylinder; and

Figure 6 represents a unidirectional frictional clutch which binds the reel driving gear to the reel shaft.

Referring to the drawing the reel comprises at least three separate reel members 10, 11 and 12. A plurality of bar members 13, 14 and 15 which form the peripheries of each of the reel-members are interleaved to form a single, combined periphery. Each set of bar members of a reel member, however, is adapted to rotate about its own axis. All reel member axes are offset and askew to each other. By being mounted on separate and individual offset and skewed axes a portion of the periphery of each reel member is adapted to emerge outside of the combined reel member peripheries for an instant during each revolution of the reel to effect an advancement of thread or the like. At least two reel members of the three will advance the thread in consecutive forward movements over the reel periphery.

As shown in Figure 3 the bar members 13 of the reel member 10 are supported by a hub 17 which is concentrically mounted on the shaft 18. The hub 17 is secured to the shaft 18 by means of the set screw 19. The reel member 10 thus rotates with the shaft 18. The bar members 14 and 15 which comprise the peripheries of reel members 11 and 12, are also similarly supported. The bar members 14 comprising the periphery of the reel member 12 are supported by the hub member 20, and the bar members 15 of the reel members 13 are supported by the hub 21. The hub members 20 and 21 are rotatably mounted on the eccentric members 23 and 24 whose axes are offset and askew to the shaft 18 and to each other.

The eccentrics 23, 24, as shown in Figure 4 are conveniently made a part of the entire reel supporting structure 25. Also, as shown, the shaft 18 is positioned within the supporting member 25 and extends therethrough so that, desirably, the reel member 10 is mounted on the protruding shaft portion. On the other end of shaft 18 there is mounted a driving gear 34. The gear, as shown, is held securely to the shaft by a set screw 35. Thus, by rotating the gear 34 the reel member 10 is adapted to drive the other two reel members 11 and 12 through contact of the bars. Anti-friction bearings are desirably provided for the shaft and the reel members. The shaft 18 rotates in an anti-friction bushing bearing 27, while the hub members 20 and 21 rotate on the anti-friction bearings 28, 29 which are mounted on the eccentrics 23 and 24. Lateral displacement of the reel-members is also prevented. Shoulders 31 and 32 are provided on the support 25 against which the hub members 20 and 21 abut. Spring retaining washers 36, 37 are utilized to maintain the reel members in position.

The aforesaid assembly of elements provides a simple and a unitary reel that is adapted, when driven, to advance thread in a helical fashion over its periphery, the advancement of the thread being effected in at least two increments for each complete revolution of the reel. The eccentric axes and the relative disposition of the bar members of the three reel members enable one set of bar members to protrude in an advancing manner above the other sets to advance thread for each revolution of the reel. Such an advance-

ment of the thread is more progressively uniform than if it were moved but once during each complete rotation of the reel.

In a process where artificial thread or the like is continuously produced the herein described reels are advantageously positioned in a vertical series with their unobstructed ends facing outwardly toward the operator. Such a positioning of the reels enables the operator to readily perform his tasks inasmuch as the reels are accessible for threading up purposes, inspection, etc. Where a plurality of reels such as the reel herein described are positioned in a vertical series the thread or the like is usually dropped from a higher positioned reel to the reel below to be threaded thereon. The thread is dropped in a similar manner to all succeeding reels. Should, however, some difficulty appear on any one of a vertical series of reels during thread processing or during a threading-up operation normally an entire series of reels must be stopped from rotation in order to correct such a condition. Further, if such a reel continues to rotate it may not be desirable to have the thread advance over it while the fault is corrected. Should an unforeseen difficulty arise in a processing stage and it is not desirable to stop the rotation of the remaining reels of a series the reel of this invention under such circumstances can be converted into a non-advancing reel or a cylinder to merely wind thread thereon in the form of a bundle. Such a reel is shown in a modification represented by Figure 5.

In the modification of Figure 5 the eccentric members 23 and 24 advantageously form a part of a sleeve 40 or are attached thereto. The sleeve 40 is splined or it may have a keyway 41 at one end. About the sleeve 40 there is positioned a bushing bearing 42 and about the bushing 42 the reel supporting sleeve 43. Desirably sleeve 43 has a flared portion 44 which is adapted to be received by a retaining means (not shown) in a spinning apparatus to be firmly and rigidly held thereby.

The reel shaft 18 protrudes outside of the sleeve 40 so as to permit the mounting of a driving gear 45 on such extension. The gear 45 is held to the shaft 18 by a set screw 47. Gear teeth 48 are also provided on the hub portion of the gear 45. Gear teeth 50 are also provided on the end of the supporting sleeve 43. A splined or keyed collar 51 adapted for lateral movement is mounted about the eccentric sleeve 40. The collar 51 has an internal gear 53 which is adapted to mesh with the hub gear 48, and an internal gear 54 which is adapted to mesh with the sleeve mounted gear 50. The collar also has an annular groove 56 into which extends a yoke 57. The yoke 57 forms one end of a bell-crank 60 which rotates about a pivot 61 fixed to the flared reel support 44.

As shown, the position of the bell-crank 60 has effected a meshing of the internal gear 53 with the hub gear 48. Any rotation of the driving gear 45 will as a result cause a rotation of both the reel shaft 18 and the eccentric sleeve 40 since the collar 51 is splined to the eccentric sleeve. When both the shaft and the eccentric sleeve are rotated at the same time there will be no advancement of thread over the reel periphery. The reel is thus reduced to a cylinder inasmuch as its function now is only to wind thread and not to advance it over its periphery. The thread is wound in a circular bunch. Such an accumulation, of course, can be removed at any desired moment by reconverting the reel to a thread

advancing reel from that of a cylinder. This is easily done by shifting the collar 51 away from the driving gear 45 and holding the eccentric sleeve 40 from rotation.

When the collar 51 is shifted by the bell-crank 5 to effect a meshing relation between the internal gear 54 of the collar and the gear 50 on the supporting sleeve 43, the eccentric sleeve 40 is stopped from further rotation since it becomes fixed to the reel support sleeve 43. The eccentric sleeve 40 is held rigidly through the splined collar and gears 50, 54. With the eccentric sleeve 40 being held the reel members 10, 11 and 12 will rotate on fixed axis that are eccentric to each other, causing an advancement of the accumulated bunch of thread on the reel.

Further, there sometimes occurs a need for an over-running clutch which will allow a reel to rotate at a rate in excess of its driven rate without disengaging the reel from its normal power source. There is provided by this invention a driving gear mounted on a unidirectional clutch which will permit a reel to be rotated, because of some additional external driving force, as a greater draw-off rate of thread by a subsequent reel, exceeding the normal rate without disengaging the reel from its power source.

As shown in Figure 6 of the drawing the reel driving gear 45 is desirably mounted on a unidirectional clutch 65. The clutch may be formed by the driving gear 45 and a sleeve 66. The roller bearings, of course, are positioned between the sleeve and the gear. The sleeve is, of course, fixed to the shaft 18. Further a collar 67 is mounted on the end of the shaft 18 and abuts the driving gear 45. The collar 67 is held on the shaft 18 by a set screw 68. Any displacement therefore of the unidirectional clutch 65 is prevented by the collar 67. Then by being mounted on a one-way clutch 65 the gear 45 will cause 40 the rotation of the shaft only in a predetermined direction which direction is, of course, the one that is adapted for winding an advancing thread by the reel. Should such a reel temporarily exceed its driven rate because of some externally applied force increasing its rate of rotation in the same direction, it will, when such condition has passed, be again picked up by the clutch 65 to be driven at the normal predetermined rate.

Thus there is further provided by this invention a reel which can be reduced to perform the functions of a winding cylinder from those of an advancing reel and one which can be accelerated to higher speed without disengaging it from its power source.

I claim:

1. A thread or the like winding and advancing reel comprising a plurality of separate reel members having peripheries of a plurality of individual supported bar members; said bar members being positioned in an interdigitating relation forming a combined, generally circular reel periphery; individual axes of rotation for said reel members, said axes being offset and askew to each other; a shaft about which said reel members are mounted; means for supporting said reel from one end only, said means comprising a sleeve through which extends the shaft supporting said reel; one of said reel members being mounted on one end of said shaft; a sleeve about said shaft for rotationally supporting at least one of said reel members; said member supporting sleeve being positioned within said reel supporting sleeve; a driving gear mounted on one end of said reel supporting shaft, said driving gear

having gear teeth on its hub end; a splined sleeve positioned about the sleeve rotatably supporting at least one of said reel members; teeth on one end of said reel supporting sleeve; and said splined sleeve having gear teeth in each end which are adapted to mesh with the teeth on said reel supporting sleeve or teeth on said driving gear to thereby hold said reel member supporting sleeve stationary or to hold said reel member supporting sleeve to the driving gear to rotate with said reel shaft.

2. A thread or the like winding and advancing reel comprising at least three separate reel members each having a periphery of a plurality of bar members, the bar members of each reel member interdigitating and being coextensive with the others, and said reel members being mounted on offset and askew axes arranged so that at least two of said reel members are adapted to advance thread and the like during each revolution of the reel.

3. A thread or the like winding and advancing reel comprising at least three separate reel members each having a periphery of a plurality of bar members, the bar members of each reel member interdigitating and being coextensive with the others, a shaft, one of said reel members being mounted concentrically about said shaft, eccentrics positioned about said shaft for rotatably mounting said remaining reel members, and the axes of said eccentrics being offset and being arranged with respect to each other and with respect to said shaft axes so that each of the eccentric mounted reel members is adapted to advance thread during each revolution of the reel.

4. A thread or the like winding and advancing reel comprising at least three separate reel members each having a periphery of a plurality of bar members, the bar members of said reel members being in an interdigitating relation and coextensive with each other, said reel members being mounted for rotation about axes that are offset and askew to each other, and said axes being fixed against rotation so that each of two of said reel members is adapted to advance thread and the like in series relation during each revolution of the reel, the advance of the thread and the like occurring at substantially the same circumferential positions for each revolution.

5. A thread or the like winding and advancing reel comprising, two eccentrically disposed sets of bars occupying substantially the same space, each set of bars having thread supporting surfaces lying in a substantially cylindrical surface, a rotatable shaft, means for supporting the reel positioned about the shaft, means on one end for driving said shaft, one of said sets of bars being secured to said shaft for rotation therewith, an eccentric rotatably mounted on said shaft, the other said bars being rotatably mounted with respect to said eccentric, and means positioned at about the driving end of said shaft for connecting said eccentric to said reel supporting means for maintaining said eccentric stationary or for connecting said eccentric to said shaft for rotation therewith.

6. A thread or the like winding and advancing reel comprising, a plurality of eccentrically disposed sets of bar members occupying substantially the same space, the bar members of each of said sets having their thread supporting surfaces lying in a substantially cylindrical surface, a rotatable shaft, one of said sets of bar members being substantially concentrically

secured to the shaft for rotation therewith, an eccentric rotatably mounted about said shaft having a plurality of bar members set supporting portions having axes that are offset and askew to said shaft, the said sets of bar members being rotatably mounted on said eccentric, and means positioned about the shaft for maintaining said eccentric stationary or for connecting said eccentric to said shaft for rotation therewith.

7. A thread or the like winding and advancing reel comprising a plurality of eccentrically disposed sets of bar members occupying substantially the same space, the bar members of each of said sets having their thread supporting surfaces lying in a substantially cylindrical surface, a rotatable shaft, one of said sets of bar members being substantially concentrically secured to said shaft for rotation therewith, an eccentric rotatably mounted about said shaft having a plurality of bar member set supporting portions having axes that are offset and askew to each other, the said sets of bar members being rotatably mounted on said eccentric and arranged thereon in a manner so that each

set is adapted to advance thread and the like once during each revolution of the reel, and means positioned about the shaft for maintaining said eccentric stationary or for connecting said eccentric to said shaft for rotation therewith.

5 THOMAS S. MAYNER.
